ABSTRACT: Method and apparatus for wrapping flat articles wherein each article with its wrapping material is pushed through a folding tunnel for the purpose of partially folding the wrapping material about the article, and each article is then transported to a final folding station; additional folding operations being performed during the transport. The next cycle of operations in the apparatus is begun during this transport.

DEVICE FOR WRAPPING ARTICLES

The present invention concerns a method for wrapping articles, such as chocolate tablets for instance, in which the wrapping is begun by passing the articles each with its wrapping material one after the other through a folding shaft.

In the case of wrapping machines, for instance for wrapping chocolate tablets, it has long been usual to provide a so-called folding shaft, or tunnel through which the combination of the article to be wrapped together with its wrapping material is pushed in order to achieve a partial folding.

The folding shaft offers the great advantage that the packing machine is not only simple in construction but also simple to operate and achieves a folding of pleasant appearance to which the consumers have long been used.

The rate of ejection of packing machines with folding shafts has however been limited up to the present time by the fact that in the case of the known machines all the folding operations following the folding shaft are carried out within reach of the folding shaft.

The purpose of the present invention is to eliminate this disadvantage and to increase the rate of ejection of a packing machine with a folding shaft without at the same time increasing the speed of operation, respectively the acceleration of the individual machine components. This purpose is achieved according to the invention by effecting only part of the folding operations in the neighborhood of the folding shaft and the following folding operations away from the said neighborhood so as to free this neighborhood rapidly and increase the rate of ejection of the machine without increasing the speed of operation, respectively the acceleration of the individual machine components.

Owing to the fact that according to the invention the said neighborhood is freed earlier than in the case of known machines, it is possible to proceed conveniently in such a manner that the folding operations are continued whilst the packing material partially folded round the article is still partially in the folding shaft, the folding is proceeded with whilst the article is being transported to a final folding station, and the following cycle of operations is already begun during this transport, by the introduction of the following article with its packing material into the folding shaft.

The invention further concerns a device for carrying out the said method, with a folding shaft, through which the articles provided with their packing material are run through one after the other, and with means arranged away from the neighborhood of the folding shaft to continue and finish the folding of the packing material around the articles.

This device is characterized according to the invention by means which lead the partially packed article away from the neighborhood of the folding shaft to a final folding station, in order to free this neighborhood rapidly and to increase the rate of ejection of the machine without increasing the speed of operation, respectively the acceleration of the individual machine components.

The device is conveniently designed in such a manner that the means arranged away from the neighborhood of the folding shaft comprise folding members which at the same time form transport members conceived in such a manner that, on the one hand they begin the folding operations on the article leaving the folding shaft whilst the partially folded packing material is still partially in the folding shaft, and on the other, continue the folding operations whilst they are transporting the partially wrapped article towards the final folding station, a new cycle of folding operations beginning on the following article already during this transport.

In the following, an embodiment of the invention is described in greater detail by way of example with reference to the appended drawing and its advantage compared to known machines is explained.

FIGS. 1 to 3 show three successive phases of the operation of a packing machine in side elevation and partially in cross section, parts which are not essential to the invention being left out.

FIGS. 4 to 6 show three successive phases of the operation of the transversal folders, partially in cross section.

FIG. 7 shows a view from above of the machine according to FIGS. 1 to 6.

FIG. 8a shows (for purposes of comparison) a simplified diagram of the successive motions of a known machine with a folding shaft, whilst FIG. 8b shows a corresponding diagram of the machine illustrated in FIGS. 1 to 7.

The illustrated machine has a transport chain 1 which runs round a wheel 2 and is provided with pusher fingers 2a. These move tablets of chocolate 3a, 3b, 3c— on a support (not shown) towards a folding station, described in greater detail below.

At least one foil 4 is fed in sections in a known manner from a roll (not shown) towards the folding station. In addition, paper blanks 50 are brought from a magazine 5 and placed on the foil sections in the folding station, which is also effected in a manner known per se by means of jaws 6.

The folding station is primarily provided with a folding shaft or tunnel 7, which can be made to slide perpendicularly by means of a tappet 8. A lower transporter 9 and an upper transporter 10 operate within the folding shaft. The lower transporter 9 is a ram, the rod 11 of which slides in a guide 12 and is actuated by a lever 13. The upper transporter 10 is actuated by links 14, 15 and 16 of which the last is articulated in the fixed point 17. The upper transporter 10 is provided in a known manner with a shock absorber 18.

Following the folding shaft 7, the illustrated machine is fitted with a combined transport and folding member 19, which is mounted to rock on the axis 20 and acts at the same time as transversal folding member. For this purpose the member 19 is provided with transversal folders, essentially formed by two blocks 21 arranged opposite to one another.

Each block 21 is provided with a lower tongue 22 as well as with a rod 23 which carries a coil spring 24. This latter is engaged in a bore 25 of the block 21 and there bears against a wall 26, whilst its other end acts against the clamp heads 27.

A guide 28 in the shape of an arc of a circle is provided along the path along which the transport member 19 swings. A final folding station 29 is situated at the end of the guide 28. This station is provided with a movable support 30, a swinging stop 31 and a ram 32 as well as with a guide 33. The guides 28 and 33 are designed in such a manner that the guide 28 comprises a short radially and downwardly directed projection 34 and the guide 33 a somewhat longer radially and upwardly directed projection 35, the projections 34 and 35 being practically parallel to one another and forming a longitudinal folding shaft.

The movable support 30 and the ram 32 are actuated by links swinging about the axis 36, guides and rods (known per se) which are not described in greater detail being provided.

An ejector 37 which swings about the axis 20 and acts along a fixed lateral guide 38 is arranged after the final folding station 29 with its longitudinal folding shaft 34, 35. Finally, two transport clamps 39 and 40 acting horizontally over a short distance and actuated by levers 41, respectively 42 articulated on the axis 43 follow this ejector 37.

The illustrated machine operates as follows:

The tablets of chocolate 3 are pushed by the pusher fingers 2a towards the lower transporter 9. By means of a pusher which is not shown, the tablets are slid onto the head of the lower transporter 9. At the same time, the upper face of the tablet is provided at this point with a section of the web 4 as well as with a paper blank 50, this being effected by the clamp 6. In order to simplify the drawing, the section of the web 4 lying on the chocolate tablet 3 is not differentiated particularly from the paper blank 50.

In this position, illustrated in FIG. 1, the upper transporter has also penetrated with its holder 10 into the folding shaft 7, so that the chocolate tablet 3b together with the packing materials may be held between the lower transporter 9 and the shock-absorber 18 of the upper holder 10.

In the operating phase illustrated in FIG. 2, the clamp 6 has freed the packing material 50 and the tablet 3b is led through the folding shaft 7 by the transporters 9 and 10. At the same time this folding shaft is actuated in such a fashion that it is moved by the tappet 8 for a certain distance in the same direction as the tablet 3b, which has the advantage that the relative speed between the folding shaft 7 and the tablet 3 is reduced. In this way damage to the packing material may be avoided more easily.

In the operating phase illustrated in FIG. 3, the tablet 3b is situated at the upper end of the travel of the folding shaft 7. After the transport member 19 with its transversal folding members has become effective, the folding shaft 7 has moved towards its lower position. However, before the transport member 19 can become effective, the holder 10 of the upper transporter must be swung out of the way towards the right (FIG. 2), which is effected by means of the links 14, 15 and 16.

FIG. 4 illustrates an operating phase which occurs shortly before that of FIG. 3. The tablet 3b is still being held by the lower transporter 9 and the shock-absorber 18 of the upper transporter 10, whilst the blocks 21 of the transport member 19 begin their motion. Whilst this occurs the clamp heads 27 hold the tablet 3b resiliently, and at the same time the tongues 22 approach the edge of the tablet. Following this the tongues 22 act as transversal folders, by sliding under the tablet.

FIG. 5 illustrates an operating phase of the member 19 on its way to the final folding station 29. The lower tongues 22 are still on the way to their final position under the tablet 3. The clamp heads 27, which were already effective in the phase according to FIG. 4, are still applied against the tablet 3.

The phase of operation illustrated in FIG. 6 corresponds to that of FIG. 1, the tablet 3b of FIG. 1 having however now taken the place of the tablet 3b shown there. In this position the blocks 21 of the member 19 are completely moved aside together with all their components.

The tablet 3a rests on the movable support 30 of the longitudinal folder and is held by the projection 35 and the rockable stop 31.

For the following phases of operation reference must be made again to FIGS. 2 and 3.

As may be seen in FIG. 2, the longitudinal folding in the final folding station 29 of the tablet 3a is effected by raising stop 31 and actuating the ram 32, which pushes the tablet 3a along a longitudinal folding plane which is determined by the projections 34 and 35. It may be seen that this longitudinal folding plane has an inclination of an angle of about 45°. The finally packed tablet 3a now passes onto the rocking ejector 37.

In FIG. 3 one may see how the ejector 37 pushes the tablet 3a along a circular sector between the transport clamps 39 and 40. These pull the packed tablets in jerks along a short distance towards the left.

All the movable parts of the illustrated device are actuated and controlled in a known manner. In addition, it may be remarked that the application of adhesive is not shown and is effected in a known manner.

It may be seen that the transport member 19 moves through an arc of about 45°, which also applies to the ejector 37. It has been found that it is preferable to choose an angle of from 30° to 60° for the path of the member 19 and correspondingly for that of the ejector 37.

The improvement which may be achieved according to the invention will now be shortly explained by way of example with reference to FIGS. 8a and 8b.

In FIG. 8a the horizontal segments represent the time required for the forward motion of the following machine components of a known machine: lower transporter UT, transversal folder QF, longitudinal folder LF, longitudinal folder ram LFS, machine outlet MA.

FIG. 8b illustrates the corresponding forward motions of the machine according to FIGS. 1 to 7. It may be seen that the lower transporter UT 9, the transversal folder QF 22, the lon-

gitudinal folder LF 30, the longitudinal folder ram LFS 32 and the ejector A 37 require the same time for their forward motion as is the case in the known machine.

As may be seen the motion of the transport member 19 occurs between the motions of the transversal folder 22 and the longitudinal folder 30.

Whilst in the known machines the corresponding forward motions occur one after the other and have practically no or only little overlap, the forward motions have considerable overlap according to the invention, so that a cycle takes up less time. In FIG. 8b the gain in time per machine cycle is indicated by the letter G, and it may be seen that the gain corresponds to about 30 to 40 percent.

It is also possible to see from FIGS. 8a and 8b that in spite of the shortening of the time required for a cycle, the same absolute time interval is available for the motions of the essential components of the machine, and this means that it is possible to increase the rate of delivery of the machine (number of packed chocolate tablets per minute) without the speed of operation, respectively the acceleration of the individual components of the machine being increased.

It may be remarked, in addition, that in the FIGS. 8a and 8b only the times required for the forward motions are indicated.

I claim:

1. A device for wrapping flat articles with wrapping material comprising: a folding tunnel adapted to partially fold said wrapping material about each of said articles as the combination of each article with its wrapping material passes therethrough; a first ram movably mounted near the entrance of said folding tunnel, said first ram being adapted to move said combination through said folding tunnel; transporter means including holder means carried thereon, movably mounted near the exit of said folding tunnel, said holder means being adapted to cooperate with said first ram to move said combination through said folding tunnel, said holder means being articulated and adapted to depend from said transporter means, the length of stroke of said holder means being through said folding tunnel, such that in operation and before reaching the lower end of its stroke through said folding tunnel, it is in alignment with the longitudinal axis of said folding tunnel; a final folding station spaced from said folding tunnel; combined transport and folding means movable between the exit of said folding tunnel and said final folding station, said combined transport and folding means including holder means comprising immobilizing means, said immobilizing means being adapted to seize said combination at a point above the exit of said folding tunnel, two opposed lower tongues movably mounted in said combined transport and folding means below said immobilizing means, said tongues being adapted to move below the bottom surface of said article while concurrently pressing said wrapping material against said bottom surfaces, and means for actuating said combined transport and folding means such that said combination is transported to said final folding station while being positively held; said combined transport and folding means being adapted to travel along an arc of a circle to transport said combination away from the axis of said folding tunnel; said combined transport and folding means being adapted to begin folding operations on said combination while said combination is still partially in said folding tunnel and continue said folding operations during transport of said combination to said final folding station; said final folding station comprising a second ram adapted to move said combination radially of the direction of movement of said combined transport and folding means, a movable tongue operatively associated with said second ram and adapted to move below the bottom surface of said article while concurrently pressing said wrapping material against said bottom surface, and a stationary tongue over which said combination passes when moved by said second ram, thereby pressing said wrapping material against said bottom surface; further transporter means adapted to receive said wrapped article from said final folding station, said further transporter means being adapted to travel along an arcuate

path to eject said wrapped article from said wrapping device; and cycling means for cycling the operation of said device so that during the transport of a combination to said final folding station, another combination is introduced into said folding tunnel.

2. Device according to claim 1 wherein said final folding station is provided with a longitudinal folder, which becomes effective immediately after a combination arrives in this station.

3. Device according to claim 2, wherein the longitudinal

folder is arranged to form a ram for the wrapped article in order to eject the latter.

4. Device according to claim 2, wherein the final folding station is provided with an ejector mounted so as to be able to swing, said ejector taking over the article coming from said second ram directly and pushing it along an arc of a circle between two horizontal transport hooks acting over a short distance.
